UNITED STATES PATENT OFFICE.

JOHN SCARISBRICK WALKER, THOMAS ASCROFT WALKER, AND EDWIN ROBERT WALKER, OF WIGAN, COUNTY OF LANCASTER, ENGLAND.

AIR-VALVE.

SPECIFICATION forming part of Letters Patent No. 289,192, dated November 27, 1883.

Application filed January 13, 1883. (No model.) Patented in England November 28, 1877, No. 4,488.

To all whom it may concern:

Be it known that we, JOHN SCARISBRICK WALKER, THOMAS ASCROFT WALKER, and EDWIN ROBERT WALKER, all of Wigan, in 5 the county of Lancaster, in the Kingdom of England, have invented certain new and useful Improvements in Air-Valves, (for a part of which we have received Letters Patent in England, dated November 28, 1877, No. 4,488,) 10 of which the following is a clear and correct specification.

In the working of valves for compressing or exhausting air and other gaseous fluids it is found that the valves are apt to dance or flap 15 while the air is passing through the same, so preventing them working safely at any but a low velocity. Air, too, being such a very compressible material, great waste occurs by air collecting in the parts of blowing-engines 20 and air-pumps and re-expanding at each stroke. It is to overcome these evils that this our invention is designed. In blowing-engines the parts are either placed on the sides of the cylinders or in their ends. We have, therefore, 25 in our drawings shown two variations, so as to show the application of our invention both to the cylinder-covers and their sides. In some blowing-engines, indeed, the valves are on the cylinder-cover, at the back and on the 30 side of the cylinder at the front end.

Referring to the drawings, Figure 1 is a part plan, and Fig. 2 a section of valve apparatus on a cover of a horizontal blowing-engine, the section being taken on the line $x-x$, Fig. 1; 35 Fig. 3, partial elevation of same.

The drawings illustrate our improvement embodied in valves applied to a cylinder-head.

In the various figures, A represents the air-admission valve; B, the air-discharge valve; 40 C, the stuffing-box, through which the piston-rod will pass, and D the cylinder-cover and cylinder. The air outlet or discharge valve B is hinged at one edge to the cylinder-head in such manner as to swing outward, its inner 45 surface being made in such form as to enter and nearly fill the port or opening in order to reduce as much as possible the dead-air space. The closing of the valve B is effected by the pressure of a plunger or thimble, E, mounted 50 in a tubular guide and depressed by means of a spiral spring, G. The spring G bears at

its upper end against the vertically-movable plate H, which is in turn depressed by the second spiral spring, G', which is preferably compressed by means of a head or plate on the 55 lower end of an adjusting-screw, I, all these parts being mounted in the guide which receives the plunger E. The spring G' is to be weaker than the spring G, and is usually shorter in length. The spring G' tends to relieve or equalize any sudden shock, and the 60 spring G to act as a buffer to cushion the blow strongly at the end, the two springs serving jointly to give a smoothness and ease of action not otherwise attainable. If preferred, the 65 springs G may be replaced by a spring or core composed of india-rubber.

Referring next to the inlet-valve A, it will be seen that it is hinged at one edge of the cylinder-head in such manner as to swing inward, 70 and that, when closed, its inner surface is flush, or practically flush, with the inner surface of the head. The closing of the valve is effected by means of a link, J, attached to its outer side and pivoted at its opposite end to a plunger or piston, K, arranged to work in an 75 enclosing chamber or cylinder. To this piston a rod or spindle, M, is secured and extended upward through guide-bars N, which are secured rigidly in position by means of connecting-posts at their ends, as shown in Figs. 2 and 3. The upper end of the spindle M passes between two friction-blocks, S and S', of cast-iron or other suitable material, mounted in the 80 top of the frame N, and acted upon by a screw, 85 l, by means of which they may be caused to exert more or less friction upon the spindle, so as to retard its end motion, and thus limit the speed of the valve A.

In order to give the friction-blocks S and S' 90 a yielding pressure upon the spindle M, I prefer to introduce a rubber block or spring, L, between one of said parts and the inner end of the pressure-screw l, as plainly represented in Fig. 2.

For the purpose of effecting the upward movement of the spindle M to close the valve A, I mount around said spindle a spiral spring, 95 O, the upper end of which bears beneath a thumb-nut, P, screwed upon a threaded portion of the spindle. By turning this nut upward and downward the tension of the spring 100

may be increased or diminished, as circumstances may require. A jam-nut, P', applied immediately above the nut P, serves as a means of locking the same securely in position, so that it may not be jarred out of adjustment.

For the purpose of cushioning or checking the closing action of the valve A and relieving the parts from shocks, I provide one of the cross-bars of the frame N, in its under side, with a rubber spring or buffer, Q', encircling the valve-spindle M, and mount upon said spindle a vertically-adjustable nut, T, designed to encounter the rubber buffer shortly before the valve reaches its seat. A companion nut serves as a check by which to prevent the nut T from working out of position.

For the purpose of relieving the construction from shock when the valve opens suddenly or violently, so as to severely compress the spring O, I sustain the lower end of said spring upon a collar or washer, R, which is in turn sustained by a rubber spring or buffer, Q, mounted on top of one of the cross-bars of the frame N, as plainly represented in Figs. 2 and 3.

From the foregoing description it will be observed that there is in connection with the inlet-valve A a spindle and friction-blocks to retard its motion, a spiral spring, O, to effect its closing action, a cushion, Q, to relieve the closing-spring from strain as the valve opens, and a buffer, Q', to prevent the noise and shock at the instant that the valve completes its closing action. The necessity for the employment of the spindle and friction devices, as well as the buffers Q and Q', arises from the fact that in rapidly-running engines no spring which can be rigidly applied will prevent the tendency of the valve to dance or chatter. The friction devices avoid this difficulty, for the reason that the force required to vibrate the valve after it is open is much less than that required to operate the valve, and that consequently the friction, which is powerless to prevent the opening of the valve, is found quite strong enough to prevent the chattering action. By employing both the metallic spring O and the india-rubber buffer Q we obtain a quick action of the valve, combined with a rapid buffering action at the finish of its movement, the spring and buffer combined giving a smoothness of action unobtainable with the single spring of great movement. For the same reasons we prefer to have the two springs of the outlet-valve B—one of india-rubber or stiff metal, with little play, to act in the last instant, the other of steel, to govern the greater motion of the valve. India-rubber washers inserted between the springs G' and G may be employed for this purpose. These washers, if arranged to bear at the periphery against the guides, would

have an action similar to that of the friction-block S in the inlet-valve; but their use is not advised, except in engines running at very high speeds.

We claim as our invention—

1. In an air pump or engine, a valve, combined with a closing-spring and a friction device, substantially as shown, to prevent the valve from chattering.

2. In combination with the air-controlling valve, the spring O, the block K, connected therewith, the spindle M, friction-block S, and compressing device l, whereby a varying degree of friction may be applied to limit the closing action of the valve.

3. The combination of the valve A, link J, spindle M, the closing-spring O, and an adjustable friction device acting upon the spindle, substantially as shown.

4. The combination of the spindle M and spring O with the regulating device P, bearings R, and rubber buffer Q, for the purposes described.

5. The combination of the spindle M, valve A, nuts T, and rubber ring Q' on the frame, to break the force of the shock of the valve in closing and cushion strongly at the end of its movement to prevent noise.

6. The combination of the valve B, the plates E and H, and the two springs G and G'.

7. In combination with a rapidly-working valve, A, a spring, O, a friction device, S, to prevent dancing, and a cushioning device, Q Q', for cushioning strongly at the end of the stroke.

8. In combination with the valve A and its closing-spring O, the adjustable friction device acting upon the spindle, and means, substantially as described, for adjusting the tension of the closing-spring, whereby the force of the closing-spring and the degree of friction opposed to the closing action may be varied independently as required.

9. In combination with the valve A and its spindle M, the spring O, the stationary frame N, and the cushions Q Q'.

10. In combination with the valve B, the long spring G, the superposed spring G', shorter in length but of greater strength than the first-named spring, and means for varying the tension of the springs, substantially as described.
